[57] CLAIM

The ornamental design for a table leg, as shown and
described.

DESCRIPTION

FIG. 1 is a perspective view of a table leg, showing my
new design;

FIG. 2 is a bottom plan view;

FIG. 3 is a top plan view;

FIG. 4 is a side elevational view; and

FIG. 5 is an elevational view showing the side opposite
that shown in FIG. 4;

The two undisclosed sides are the same in appearance as
the sides shown in FIG. 4.
